no shed ball bearing or equivalent to be used. The ball bearing is not required to be used, but may be used if desired. The handlebar 3 is pivotally mounted at one end to said runway member 1 at one side thereof. The mounting for the handlebar 3 comprises a disk end 4 on said bar and a rivet 5 extending through the center of said disk end 4 and through a radial external ear 6 on said runway member 1, the arrangement being such that the handlebar 3 is swingable in a plane parallel to that of the runway member 1 into overlying diametrical relation to said runway member, or, into different angular positions at one side of said runway member tangential thereto.

Snap action detent means is provided for yieldingly locking the handlebar 3 in its different positions.

The snap action detent means comprises a circular series of ball members 7 between the disk end 4 of the handlebar 3 and the ear 6 grouped around the rivet 5 concentrically, and complementary punched out arcuate sockets 8 in

UNITED STATES PATENT OFFICE

2,614,361

BALL AND RUNWAY TOY AND HANDLE THEREFOR

Michael P. Marong, Warsaw, N. Y.

Application November 17, 1950, Serial No. 196,273

2 Claims. (Cl. 46—43)

1

My invention relates to improvements in ball and runway toys, and more particularly to handles therefor.

The primary object of my invention is to provide in such toys an inexpensive handle for an annular ball runway member and which is adjustable selectively into a number of different set positions to facilitate manipulating the runway member in a manner to cause a ball to run around the member while said member is held in different positions so as to make the toy more interesting.

Other and subordinate objects, within the purview of my invention, together with the precise nature of my improvements, will be readily understood when the succeeding description and claims are read with reference to the drawing accompanying and forming a part of this specification.

In said drawing:

Figure 1 is a view in plan of my improved toy in the preferred embodiment thereof;

Figure 2 is a view in edge elevation;

Figure 3 is a fragmentary view in perspective; and

Figure 4 is a fragmentary view in transverse section taken on the line 4—4 of Figure 1 and drawn to a larger scale.

Referring to the drawing by numerals, according to my invention as illustrated, an internally grooved, annular runway member 1, in which a ball 2 is caused to roll by manipulation of said member, is provided with a straight flat handle bar 3 of resilient material, preferably a plastic.

The handlebar 3 is pivotally mounted at one end to said runway member 1 at one side thereof. The mounting for the handlebar 3 comprises a disk end 4 on said bar and a rivet 5 extending through the center of said disk end 4 and through a radial external ear 6 on said runway member 1, the arrangement being such that the handlebar 3 is swingable in a plane parallel to that of the runway member 1 into overlying diametrical relation to said runway member, or, into different angular positions at one side of said runway member tangential thereto.

Snap action detent means is provided for yieldingly locking the handlebar 3 in its different positions.

The snap action detent means comprises a circular series of ball members 7 between the disk end 4 of the handlebar 3 and the ear 6 grouped around the rivet 5 concentrically, and complementary punched out arcuate sockets 8 in

5 said disk end 4 in which said ball members 7 are adapted to seat. Resilient plugs 9, preferably of rubber, fitted in cylindrical sockets 10 in the ear 6 yieldingly urge the ball members 7, which project part way into the sockets 10, outwardly of said sockets 10 into the sockets 8.

Coacting devices are provided on the free end of the handlebar 3 and on said runway member 1 for yieldingly locking the handlebar 3 to said runway member 1, with a snap action, when said handlebar 3 is swung into diametrical relation to said runway member 1. For this purpose, the free end of the handlebar 1 is provided with a hooked flange, or end, 11 adapted to be positioned by swinging of the handlebar 3 into straddling relation to one side edge of the runway member 1 when the handlebar 3 is swung into diametrical relation. An external lug 12 on said runway member 1 is provided for snapping into 15 a slot 13 in said flange 11 when the handlebar 3 is in diametrical relation to the runway member 1.

As will be seen, the handlebar 3, in addition to being swingable into diametrical relation to the runway member 1, may also be swung into radial outstanding position relative to said member, as well as into different tangential positions relative to said member so that by setting said handlebar and grasping the same, the runway member may be held in a number of different positions relative to a hand grasping said handlebar so as to render the toy interesting in manipulating the same to cause the ball 2 to run around said runway member 1. To facilitate grasping the handlebar 3, the same may be serrated, as indicated at 14.

The foregoing will, it is believed, suffice to impart a clear understanding of my invention without further explanation.

Manifestly, the invention, as described, is susceptible of modification, without departing from the inventive concept, and right is herein reserved to such modifications as fall within the scope of the appended claims.

Having described my invention, what is claimed as new is:

1. An annular internally grooved ball runway member for manipulation to cause a ball in the groove to roll around the same, a radial external ear on said member coplanar therewith, a handle bar having a disk on one end, an axial pivot extending through said disk and ear and swingably connecting said handle bar to said ear for relative swinging over and clear of said member into different positions to facilitate manipulation of

said member, snap action means on said member and the other end of said bar for yieldingly retaining said bar in diametrical relation to said member comprising a slotted resilient hook on said other end of the bar adapted to straddle said member, and a lug on said member for engaging said slot, and coacting snap action detent devices on said ear and disk for yieldingly retaining said bar in different positions when swung out of diametrical relation to said member.

2. An annular internally grooved ball runway member for manipulation to cause a ball in the groove to roll around the same, a radial ear extending from said member coplanar therewith, a handle bar, a pivot extending through one end of said bar and into said ear for swingably connecting said handle bar to said ear for selective swinging over and clear of said member into different positions to facilitate manipulation of said member, and a snap action means on said member and the other end of said bar for yieldingly retaining said bar in diametrical relation to said

member comprising a slotted resilient hook on said other end of said bar adapted to straddle said member, and a lug on said member for engaging said slot.

MICHAEL P. MARONG.
